ATTACHMENT FOR CARBURETORS

Arthur Point, Seekonk, Mass.

Application March 18, 1935, Serial No. 11,627

5 Claims. (Cl. 123—122)

This invention relates to an attachment for a carburetor of the type generally used with internal combustion engines; and has for one of its objects the provision of greater efficiency in the operation of the engine of which it is a part of the equipment.

Another object of the invention is the provision of a simple and inexpensive attachment which may be mounted without difficulty upon a carburetor of an engine.

Another object of the invention is to supply warm air to the carburetor to better pick up and gasify the fuel with which it comes in contact.

With these and other objects in view, the invention consists of certain novel features of construction, as will be more fully described, and particularly pointed out in the appended claims.

In the accompanying drawing:

Fig. 1 is an elevation of a portion of an engine illustrating the carburetor with my device positioned on the far side thereof;

Fig. 2 is an elevation showing the carburetor and my device attached thereto, looking at right angles to the position of Figure 1;

Fig. 3 is an elevation of my attachment compartment alone;

Fig. 4 is a sectional view substantially on line 4—4 of Figure 3;

Fig. 5 is a perspective view of the shield.

With reference to the drawing, 10 designates a portion of an engine block having an intake manifold 11 and an exhaust manifold 12. A block or suitable elevating support 13 forms a mounting for the carburetor designated 14 which is secured thereto by means of cap screws 15 extending through the base portion 16 thereof. A fuel control lever 17 is pivoted at 18 and operated by the rod 19 from some suitable point of actuation to control the amount of fuel supplied to the engine. The air intake for the carburetor consists of an opening, designated 20 and is surrounded by a tubular boss or nozzle 21.

In order to control the supply of air to this intake nozzle or opening 20, I have provided an attachment in the form of a closed compartment, designated generally 22 which consists of a generally rectangular box having opposite side walls 23, 24, edge walls 25, 26, top wall 27 and a bottom wall 28. A conduit or tube 29 extends from the walls 23 at a point adjacent its upper end and fits about the boss 21 while packing 30 provides an air tight connection thereto.

The opposite wall 24 of this compartment is provided with an opening 31 having a boss 32 extending therefrom with a longitudinal bore 33

and a valve seat 34. A lateral opening 35 communicates with the bore adjacent the valve seat while the flow through the opening 31 is controlled by means of a threaded member 36 having a head 37 and a conical valve 38 for engaging the valve seat 34. I term this opening the primary opening because of the more or less permanent adjustment given to the member 36 to provide a constant entrance of the air to the opening 31 for the admission of air into the compartment.

At a lower location in the wall 24, I provide a secondary opening 40 at one side of the center and a closure door or cover 41 of a size considerably larger than the opening and which is hinged to the wall 24 on a pintle pin 42 and provided with a spring 43 to swing this door 41 to close the opening while an arm 44 is connected to this cover or door 41 to move the same a certain amount away from the opening to control the admission of air to the compartment.

The arm 44 extends to a point beyond the side wall 26 and is there provided with an enlargement 45 having an opening 46 therein and a set screw 47 for securing a rod 48 in the opening in different adjusted positions. The arm 44 moves this flapper or door 41 varying amounts away from the opening to permit more or less air to enter the compartment and shield any forceful admission of air flowing at substantially right angles to the wall 24. The rod 48 extends to and connects with the offset end 49 of the rod 19 by means of an L-shaped portion 51 extending through an opening in the offset 49. A helical spring 50 holds this portion 51 in position. By this arrangement upon movement of the rod 19 and the lever 17, the rod 48 moves the cover 41 to and from open or closed position, as shown in Fig. 2, the arrangement being such that when the amount of fuel supplied is increased, a greater opening into the compartment will be provided.

I conduct the warm air from about the engine into the openings in the compartment and to assist collecting and directing the warm air, I have provided a shield as at 55 which is of a shape best shown in Figure 5. It has an opening 56 for the entrance of air to its upper end for supplying the primary opening 31, whereas the air also enters the bottom at 57 to be conducted to the opening 40 which is variably controlled.

A shield 58 extends to a point considerably below the compartment to assist in the conduct of air from about the engine into the shielded space 59 mentioned and which may be adjusted by means of a slot 60 in the shield and a binding screw and nut 61 and 62 to vary the size of the 55

opening 56. This shield 55 which covers the openings and serves to conduct the heated air thereinto also serves by itself becoming heated to warm the air which will enter the compartment and 5 also serves to provide a disturbed supply of air to the openings shielded, especially protecting them from a direct force which may be imparted to the air by means of a fan which forces the air backwards over the engine when the same is 10 used in an automobile having a forward radiator.

By this attachment, I have found by tests which I have made that I can effect a saving of from 20 to 25% in the consumption of gasoline on a Chevrolet automobile.

15 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In combination with an engine having an intake manifold, a carburetor connected thereto 25 and having an air intake opening and a throttle control, a compartment communicating with said opening and through which all air received in said opening must pass, said compartment having a primary opening for the entrance of cold air in a fixed amount, a secondary opening, means for 30 conducting air over the warmed parts to said secondary opening, and means operable from the throttle control for variably controlling the secondary opening to open the same as the throttle 35 control is advanced.

2. In combination with an engine having an intake manifold, a carburetor connected thereto and having an air intake opening and a fuel supply valve, a compartment communicating with 40 said opening and through which all air received in said opening must pass, said compartment having a primary opening for the entrance of cold air in a fixed amount, a secondary opening, means for 45 conducting air over the warmed parts to said

secondary opening, and means for variably controlling the secondary opening in time with the fuel supply valve to open the same as the fuel valve is opened.

3. In combination with a carburetor having an air intake opening and a throttle control, a compartment communicating with said opening through which all air received in said opening must pass, a primary opening to said compartment for the entrance of cold air, means for fixedly adjusting the size of the passage through said primary opening, a secondary opening, means for conducting air over the warmed parts to said secondary opening, a cover for said secondary opening, and means for hingedly mounting said cover 15 to cover or move from covering position over said opening in varying amounts in response to the throttle control.

4. In combination with an engine having an intake manifold and an exhaust manifold, a carburetor connected thereto and having an air intake opening, a compartment communicating with said opening and through which all air received in said opening must pass, said compartment having a primary opening for the entrance 20 of air in a fixed amount, a secondary opening, means for variably controlling the secondary opening, and a shield adjacent the variable opening for directing the air currents with reference thereto.

5. In combination with an engine having an intake manifold and an exhaust manifold, a carburetor connected thereto and having an air intake opening, a compartment communicating with said opening and through which all air received in said opening must pass, said compartment having a primary opening for the entrance 25 of air in a fixed amount, a secondary opening, means for variably controlling the secondary opening, and a shield over said openings for directing warm air about the engine into said openings.

ARTHUR POINT.
